CLAIM

The ornamental design for a swimwear or underwear with dual-waist loops, as shown and described.

DESCRIPTION

FIG. 1 is a top view of the swimwear or underwear with dual-waist loops in an open configuration;

FIG. 2 is an isometric view of the swimwear or underwear with dual-waist loops illustrated around the waist of a human male unclaimed as part of this design;

FIG. 3 is a front view of the swimwear or underwear with dual-waist loops illustrated around the waist of a human male;

FIG. 4 is a front isometric view of the swimwear or underwear with dual-waist loops as illustrated at FIGS. 2-3 without illustrating the human;

FIG. 5 is a back isometric view of the swimwear or underwear with dual-waist loops as illustrated at FIGS. 2-3 without illustrating the human;

FIG. 6 is a right side isometric view of the swimwear or underwear with dual-waist loops as illustrated at FIGS. 2-3 without illustrating the human;

FIG. 7 is a left isometric view of the swimwear or underwear with dual-waist loops as illustrated at FIGS. 2-3 without illustrating the human;

FIG. 8 is a top isometric view of the swimwear or underwear with dual-waist loops as illustrated at FIG. 1 in a worn configuration without illustrating the human wearing the product;

FIG. 9 is a bottom isometric view of the swimwear or underwear with dual-waist loops as illustrated at FIG. 1 in a worn configuration without illustrating the human wearing the product; and,

FIG. 10 is a second illustration of the swimwear or underwear with dual-waist loops as illustrated at FIG. 1 but worn with the two loops placed at different positions around the waist of a human than the illustration shown at FIG. 2.

Illustrated as FIGS. 1-10, is a new swimwear or underwear for both males and females with dual-waist loops as illustrated.

The broken lines in the drawings depict stitching and form no part of the claimed design. The broken lines showing the humanoid figure are for purpose of illustrating environment and form no part of the claimed design.
